[57] CLAIM

The ornamental design for a recreational boat, as shown and described.

DESCRIPTION

FIG. 1 is a side elevational view of a recreational boat showing our new design, the opposite side elevational view being a mirror image of that shown;
FIG. 2 is a front elevational view thereof;
FIG. 3 is a top plan view thereof;
FIG. 4 is a bottom plan view thereof;
FIG. 5 is a rear elevational view thereof; and
FIG. 6 is a top and side perspective view thereof.
